FIG. I

FIG. 2

UNITED STATES PATENT OFFICE

2,555,821

CLOTHES DRIER

Marvin M. Smith, Muncie, Ind.

Application April 22, 1950, Serial No. 157,573

2 Claims. (Cl. 34—76)

1

This invention relates to the drying of fabrics, and particularly to domestic clothes driers.

The main objects of this invention are to provide improved operating procedure and improved construction for use in clothes driers; to provide improved means for removing moisture from fabrics such as washed garments in a simple operation of relatively short duration; and to provide an improved construction for domestic clothes driers for operation in accordance with such method.

A specific embodiment of this invention is shown in the accompanying drawings in which:

Figure 1 is a sectional elevation of a clothes drier constructed according to this invention, the section being taken on the axis of rotation of the centrifugal clothes tumbler.

Fig. 2 is a diagrammatic layout showing the drier in relation to an appropriate form of operating mechanism.

In the form shown in Figure 1, the container for the clothes to be dried is in the form of a centrifugal tumbler 1 carried by a shaft 2 journaled on a horizontal axis and enclosed in an airtight housing 3 having a door 4 opposed to the open end 5 of the tumbler 1.

The peripheral portion 6 of the tumbler 1 is of perforated or other foraminous form to permit of the free passage of moisture and vapor through it. The back wall 7 may be formed of unperforated metal and there is an inwardly curved marginal rim 8 around the open end of the container which tends to confine the contents and prevent them from shifting outward during the rotation of the tumbler. To facilitate tumbling there may be baffles 7.1 on the conical rear portion thereof.

The housing 3 is in the form of an airtight cabinet, which in the form illustrated is made up of a rear part 9 and a front part 10 having registering rims 11 and 12 that are formed to interfit with each other with an interposed packing 13. The rims 11 and 12 are embraced by an outer band 14 of such V-shaped cross section that the rims are pressed together by contraction of the band 14, which may be made up of a plurality of segments having flanged ends 15 bolted together at 16, the number and shape of these band segments depending upon the shape of the cabinet walls in the plane of the rims 11 and 12. The external contour of the housing in this plane is preferably circular in order to reduce the waste space in its interior to a minimum but may, of course, be varied for external appearance.

The tubular member 17 which houses the bear-

ings for the shaft 2 is mounted between the rear wall 18 of the housing and an inwardly extending support 19 in the form of a conical shell. The bearing structure has an appropriate seal 20 for confining the lubricant and preventing leakage of air through the bearings of the shaft 20.

The tumbler basket 1 is carried on the shaft 2 by a hub 21 and the rear wall 7 of the basket has a conical central portion, spaced from and in general conformity with the conical wall 19.

In order to provide means to promote the condensation of vapor within the housing, that part of the rear wall that lies between the central bearing carrying structure and periphery of the housing comprises spaced walls 22 and 23 enclosing a coolant chamber 24 which is provided with an inlet duct 25 and an outlet duct 26 for the circulation of water or other cooling medium through the chamber 24, thus providing a cold surface 26 upon which vapor will condense. The resulting water will be directed to a drain pipe 27 in the bottom wall of the housing. A gutter 28 is formed at the inner margin of the wall 22 so as to conduct condensate forming on the wall 22 around the bearing supporting structure. The drain pipe 27 has a check valve 27.1 normally closed against inflow of air and an intermediate reservoir 27.2 is provided for collecting water while the vacuum prevents flow through the check valve 27.1.

A tube 29 extends through the walls 22 and 23 in appropriate position to serve as a suction line through which air from within the housing may be exhausted by means of an appropriate pump, such as the ejector 30. This suction line is suitably arranged with a check valve 31, so that air or water will not enter the housing through it.

A radiant heating device 35 is located around the rim flange 36 of the door opening and opposite the upper part of the open end of the tumbler, and is provided with a highly polished reflector 37 for concentrating and directing radiant heat into the contents of the tumbler 1. This heater may comprise coils 38 energized by an electric circuit indicated at 39. The heater is preferably of arcuate form concentric with the axis of the shaft 2 and its reflector is formed and positioned for most effective transmission of heat to the contents of the tumbler.

The door 4 is hinged at 40 and provided with a latch member 41 having camming engagement with the stud 42 for effecting airtight closure of the door by means of the marginal packing member 43. A normally closed air valve 44, conveniently located in the door 4, controls a vent

opening for admitting air to break the vacuum and permits the door to be opened.

Power may be supplied to the shaft 2, either by an electric motor 45 belted to the pulley 46 or by other appropriate power, as for example a water motor receiving pressure from the city water supply.

In operation the moist clothes or other fabric materials that are to be dried are inserted through the door 4 into the centrifugal container 1 and the door is closed and latched. Then the motor is turned on so as to rotate the tumbler at suitable speed.

The vacuum pump is operated so as to exhaust air from the housing and create a substantial partial vacuum. The electric current is then turned on to the heating element 35, and, as the rays are directed onto the clothes as they are tumbled, the heat reaches all parts thereof vaporizing the moisture content. The heat from the heating elements and the partial vacuum cause the moisture in the clothes to evaporate rapidly and the vapor is condensed on the cold walls 22 of the condenser and passes off through the drain.

Because of the vacuum, the vaporizing point is lowered. With a vacuum of approximately 25 inches of mercury, there is a boiling point of about 133° F. and a somewhat lower vaporizing point. This produces an atmosphere up to 100% humidity in the housing. Under these conditions the vapor collects and condenses on the cold surface of the condenser and there is no need of mechanical means to direct the vapor to the condensing surface. The condensing process is rapid as there is little air to insulate or hold the vapor.

The water that drains from the condensing surface collects and is trapped in the reservoir 27.2 where it is not exposed to the heat of the drying chamber and there accordingly is no tendency for it to re-evaporate. The heat delivered radiantly to the clothes is confined within the tumbler and the vapor will condense on any walls of the cabinet that are below 133° F.

This apparatus completely dries the clothes within the cabinet and avoids the nuisance of blowing vapor and lint into the room or house.

Although but one specific embodiment of the invention is herein shown and described, it will be understood that numerous details may be altered or omitted without departing from the

spirit of the invention as defined by the following claims.

I claim:

1. A clothes drier, comprising a tumbler for the clothes, said tumbler being journaled on a horizontal axis, being open at one axial end and having a foraminous periphery, a housing surrounding said tumbler, a door in said housing adjacent the open end of said tumbler, means for exhausting air from said housing, radiant heating means directed into the open end of said tumbler for vaporizing moisture therein, cooled condensing means in said housing positioned to drain its condensate away from the contents of said tumbler, and means for draining liquid from the lower part of said housing.

2. A clothes drier, comprising a tumbler for holding the clothes, being journaled on a horizontal axis, being open at one axial end and closed at the other and having a foraminous peripheral wall, an airtight housing surrounding said tumbler, a door in said housing adjacent the open end of said tumbler, means for exhausting air from said housing, radiant heating means directed into the open end of said tumbler for vaporizing moisture in the contents thereof, means for continuously cooling a wall of said housing behind the closed end of said tumbler for condensing the vapor in said housing, a reservoir positioned to collect drainage from said cooled wall without exposing same to the heat of said heating means, and a normally closed air inlet for breaking the vacuum in said housing.
